US0D1034970S

(12) **United States Design Patent** (10) Patent No.: **US D1,034,970 S**
(45) Date of Patent: ** Jul. 9, 2024

(54) **SNAP-ON MODULE**

(71) Applicant: **Carrier Corporation**, Palm Beach Gardens, FL (US)

(72) Inventors: **Vinay Kumar Vinnakota**, Telangana (IN); **Jagadish Reddy Putta**, Telangana (IN); **Jayesh Vasudevan Nair**, Telangana (IN); **Peter Borenstein**, Palm Beach Gardens, FL (US)

(73) Assignee: **CARRIER CORPORATION**, Palm Beach Gardens, FL (US)

(**) Term: **15 Years**

(21) Appl. No.: **29/719,737**

(22) Filed: **Jan. 7, 2020**

(51) LOC (14) Cl. **24-02**

(52) U.S. Cl.

USPC **D24/127; D9/435**

(58) **Field of Classification Search**

(57) **CLAIM**

We claim, the ornamental design for a snap-on module, as shown and described.

DESCRIPTION

FIG. 1 is a top view of the snap-on module illustrating our new design;

FIG. 2 is a bottom view thereof;

FIG. 3 is a front view thereof, with the rear, left side, and right side views being identical to the front view;

FIG. 4 is an inverted view thereof; and,

FIG. 5 is a perspective view thereof.

(Continued)

The broken lines depict portions of the snap-on module that form no part of the claim.

1 Claim, 5 Drawing Sheets
